(57) **CLAIM**

The ornamental design for a baby bottle drying rack, as shown and described.

DESCRIPTION

FIG. 1 is a perspective view of a baby bottle drying rack;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view in a state of use;

FIG. 9 is a perspective view in a closed state; and,

FIG. 10 is an enlarged view of portion 10 shown in FIG. 1. The broken lines in the drawings depict portions of the baby bottle drying rack that form no part of the claimed design; The dash-dash broken lines in the drawings depict environment that forms no part of the claimed design;

The dot-dash broken lines represent boundaries of the enlarged portions and form no part of the claimed design.
